UNITED STATES PATENT OFFICE.

MILTON W. CODDINGTON, OF RUTHERFORD, NEW JERSEY.

CAR-COUPLING.

SPECIFICATION forming part of Letters Patent No. 351,964, dated November 2, 1886.

Application filed August 7, 1886. Serial No. 210,302. (No model.)

To all whom it may concern:

Be it known that I, MILTON W. CODDINGTON, of Rutherford, in the county of Bergen and State of New Jersey, have invented a new and Improved Car-Coupler, of which the following is a full, clear, and exact description.

My invention relates to an automatic car-coupler wherein a star-cam is used for retaining the connecting-link; and the invention 10 consists of the construction, arrangement, and combination of parts, all as hereinafter described and claimed.

Reference is to be had to the accompanying drawings, forming a part of this specification, 15 in which similar letters of reference indicate corresponding parts in both the figures.

Figure 1 is a sectional elevation of my new and improved car-coupler, showing a part of the connecting-link held in the coupler; and 20 Fig 2 is a front elevation of the coupler.

A represents the draw-head, formed with cavity *a*, and throat *b*, for the connecting-link *B*, and formed with upwardly-projecting arm *A'*. In the cavity *a* is journaled upon the pin *c* the 25 star-cam *C*. This is formed with four arms, the rear edge of each of which is slightly curved and rounded to fit the link, while the front edge is rounded, as shown at *c'*. In the upwardly-projecting arm *A'* is formed a cavity, *d*, in which is held the vertically-sliding pin or block *D*. The pin or block *D* is held 30 in place in the cavity by the flanges *d'*. The cavity *d* communicates with the rear portion of the cavity *a*, so that the lower end of the 35 pin *D* reaches down into the cavity *a* back of the star-cam *C*. A lug, *d''*, is formed at the

upper end of the pin *D*, for lifting the same for uncoupling the cars.

In operation the pin *D* is permitted to drop into the draw-head as far as the lug *d''* will allow. Then the cars to be coupled have simply to be backed together, whereupon the connecting-link *B*, entering the draw-head, will strike one of the arms of the star-cam and turn the cam one quarter, or thereabout, of a complete revolution. This will bring the arm above into the connecting-link, and the arm in front will have lifted the pin *D* and passed it, so the pin will have dropped just back of the arm that lifted it, where it occupies a position between said arm and the back *i* of the draw-head, so that no matter how much outward strain is brought upon the link *B* the cam and pin *D* will retain it.

To uncouple the cars, the pin *D* has simply 55 to be lifted in the cavity of the projection *A'*, which will release the cam *C*, so the link *B* can be withdrawn from the draw-head.

Having thus fully described my invention, I claim as new and desire to secure by Letters 60 Patent—

The draw-head formed with the chamber *a*, and the throat *b*, below the chamber *a*, and formed also with the vertical cavity *d*, in combination with the star-cam *C*, journaled in the 65 chamber *a* above the throat *b*, and the pin *D*, held in the vertical cavity *d*, substantially as shown and described.

MILTON W. CODDINGTON.
